UNITED STATES PATENT OFFICE.

GEORGE LAWRENCE SLACK, OF BOSTON, MASSACHUSETTS.

ELECTRICALLY-OPERATED CONTROLLING MEANS FOR HYDRAULIC ELEVATORS.

Application filed July 2, 1921. Serial No. 482,274.

To all whom it may concern:

Be it known that I, George L. Slack, a citizen of the United States, residing at Boston, in the county of Suffolk and State 5 of Massachusetts, have invented certain new and useful Improvements in Electrically-Operated Controlling Means for Hydraulic Elevators, of which the following is a specification, reference being had to the accompanying drawings.

This invention relates to plunger elevators, and particularly to means whereby they may be controlled electrically.

In all electrically actuated controlling devices for hydraulic elevators known to me, the operating valve whereby water is admitted to or released from the plunger cylinder or the casing of an equivalent operating member has been controlled through a working head and a pilot valve using water pressure, the pilot valve being operated by magnets, and as the load on the pilot valve varies so does the speed of the magnets vary, and thus the speed of stopping or starting the car varies correspondingly. Sometimes as much as two minutes will elapse before the car moves at full speed and other times only fifteen seconds elapse, and very rarely does it take the same time 30 twice in succession to start or stop.

One of the objects of my invention is to provide for a positive control of the hydraulic valve electrically.

And another object is to provide electrically operated means for starting or stopping the car at the same speed at all times and which will not vary even to the fraction of a second, notwithstanding variations in the load.

40 And a further object is to eliminate the working head, pilot valve, and the heavy operating magnets and in place thereof to use an electric motor having a constant speed to actuate the operating valve controlling the flow of water to or from the plunger cylinder.

Another object is, by eliminating the working head and pilot valve, to thereby eliminate a constant source of leakage, which 50 leakage causes the car to creep.

Still another object is to provide, in the best form of my apparatus, means for entirely preventing anyone interrupting the use of the car while it is in motion, thus 55 preventing, in the full automatic controlling mechanism, anyone on any one floor

by pressing a control button, to stop the elevator which is moving upward or downward and under the control of another person.

And still another object is to provide means whereby the circuit through the actuating mechanism is broken at any time a door is opened when the car is in motion and unless the door of the elevator is fully 65 closed.

Another object is to provide means for breaking this circuit in case a fuse blows or the current is interrupted from any cause, whether the car is in motion or not, 70 this means bringing the car to a stop immediately, but being so constructed as to bring the car to a stop gently, this mechanism doing away with the necessity which is present in all other forms of mechanism 75 of this character known to me of the car continuing to travel to the top or bottom before stopping, which is objectionable for the reason that the first impulse of the operator or occupants of the car when it is 80 found out that the car is out of control is to try and get out, which is a prolific source of loss of life.

A further object is to provide a controlling mechanism of such character that it 85 may be used either for a car switch controlled hydraulic system, a semi-automatic hydraulic system, or a full automatic hydraulic elevator system.

Another object is to provide in connection with the valve controlling the inlet and outlet of water from the plunger cylinder a constant speed motor for operating the valve, as before stated, and electrical means for operating the motor in one or the other 90 direction as required to shift the valve in one or the other direction, and means for automatically stopping the motor after the valve is shifted a predetermined distance, this means including a current switching 100 device controlled by the motor which acts to automatically switch off the current after the motor has rotated a certain distance in one direction or the other direction.

Other objects will appear in the course 105 of the following description.

My invention is illustrated in the accompanying drawings, wherein:—

Figure 1 is a diagrammatic view of the switch board Y and the wires leading therefrom;

Figure 2 is a side elevation of the motor

and limit switch actuating means, the valve casing F and the supply pipe E, the valve casing being shown in section, the switch board connected with the limit switches being diagrammatically shown;

Figure 3 is a side elevation of the floor stop mechanism, showing the wiring thereof;

Figure 4 is a diagrammatic view of the elevator with the door switch and the stop button switches, the wiring leading from the elevator being diagrammatically shown;

Figures 1, 2, 3 and 4 are to be read together;

Figure 5 is a diagrammatic view illustrating the position of the limit switches when the car is descending;

Figure 6 is a like view to Figure 5, showing the position of the switches when the car is ascending;

Figure 7 is a top plan view of the cams O, P and Q;

Figure 8 is a section on the line 8—8 of Figure 3;

Figure 9 is a side elevation of one of the holding magnets;

Figure 10 is an end elevation thereof;

Figure 11 is a side elevation partly in section of one of the direction switches;

Figure 12 is an end view thereof.

In the drawings, I have shown diagrammatically such portions of a plunger elevator as are necessary for an understanding of the mechanism. The electrical connections are also shown diagrammatically.

In these drawings, A designates the usual cylinder within which the usual plunger B of the elevator operates, this plunger carrying the car platform C. The plunger 40 moves through the usual stuffing box D and water is admitted to the cylinder A or released therefrom through a pipe E which enters the head of the cylinder just below the stuffing box in the usual manner. The pipe E is connected at one end to a valve casing F, one end F' of this valve casing 45 constituting a discharge passage. The valve casing adjacent its upper end is provided with the passage F² connected to a supply pipe F³. Operating within the valve casing is a piston valve comprising a central stem G having the spaced valves H, H' and H² mounted thereon. The piston valves H' and H² are disposed relatively close together as compared with the distance between the piston valve H and the piston valve H'. The space between the valves H' and H² is approximately slightly larger than the outlet opening from the casing F to the pipe E. The valves H and H' are spaced from each other such a distance that when the upper valve H is disposed slightly above the inlet opening F², the valve H' will be disposed slightly below the outlet pipe opening of pipe E.

It will be obvious now that when the valve stem G is raised above the position shown in Figure 2, the valve H² passes the opening of pipe E and water from the cylinder A may be discharged, while when the stem G is in the position shown in Figure 2, water can neither enter the pipe E nor be discharged therefrom, and when the stem G is lowered so as to bring the valve H' below the entrance to pipe E, communication is established between the valve H' and the pipe E so that water may enter the casing A.

Also disposed within the length of pipe E is an auxiliary controlling valve in the form of a cut-off valve, designated I, provided with a stem I' and pivoted upon a bracket extending upward from the bonnet of the valve casing I' is a lever I², pivoted to which is the stem of a small piston I³ operating within a dash pot I⁴ and designed to contain air. This piston I³ should be perforated so as to permit a very slow travel of the piston downward through the dash pot, or else the lower end of the dash pot may be formed with a valved opening I⁵. The dash pot may contain air and obviously if the opening I⁵ be greatly contracted, the descent of the piston I³ will be relatively slow. This auxiliary valve I is designed to close in case a circuit is broken and be urged to a closing position by means of the weight I⁶ mounted on the arm I². It is normally held raised by an electrically controlled latch, as will hereafter appear.

It will be obvious now that when the piston valve G is in one position, water will be supplied to the cylinder to force the plunger therein upward, and that when the car on the platform C has risen to a predetermined distance and has been stopped, the valve 105 will be shifted to the position shown in Figure 2, which will hold the car in this position, preventing the outlet of water from the cylinder, and that when it is desired that the car move downward, the valve G is shifted 110 upward so as to permit the outward passage of water from the pipe E and from the cylinder A.

Operating in connection with the valve G is a motor and an automatic limit switch 115 therefor, the motor and the limit switch being illustrated as being mounted upon a cast iron bed plate J. The motor is designated K and may be of any suitable type and has the usual motor shaft carrying the usual armature, this shaft being connected by couplings K' to a shaft section L which carries upon it a worm L' extending through a stuffing box and into a suitable casing L². This worm engages with a gear wheel N, 120 which gear wheel is attached to a shaft N' having an arm N² connected by a connecting rod N³ with the coupling N⁴ operatively connected to the upper end of the stem of valve G. When the motor operates 125

- in one direction, the gear wheel N will be turned in one direction, thus lifting the valve, and when the current reverses through the motor, the gear wheel N will be turned in 5 the other direction, depressing the valve.
- Carried upon the shaft N' and rotating therewith are three cam disks O, P and Q. The cam disk O is formed with a socket 61 at one point in its periphery, the socket being 10 disposed vertically above the axial center of the cam disks. The cam disk P is formed with a circumferentially extending groove extending approximately half way around its circumference and terminating in a 15 shoulder 63. The cam disk Q is also formed with a circumferentially extending groove approximately half the circumference of the cam disk and terminating at its end adjacent the recess in a shoulder 62. The middle cam disk O is keyed to or otherwise mounted upon the shaft N' for rotation therewith and the cam disks Q and P are mounted concentrically to this shaft N' but are rotatively adjustable therearound and 20 with relation to the cam disk O and each other. This is secured by slotting the cam disks P and Q, as at 34, there being an adjusting bolt 41 which is attached to the cam disk O and passes through the slots of 25 the cam disks P and Q and is, of course, provided with nuts. By this means these cam disks P and Q may be rotatively adjusted relative to the middle cam disk O, as before stated.
- 30 Pivots mounted on a supporting frame, plate or other supporting means above the three cam disks are three arms. The middle arm 36 has a roller at its lower end which rests within the socket 61. The upper end 35 of this arm carries a switch blade 30. The arm 35 which coacts with the cam P is likewise pivots mounted and carries a roller at its lower end which operates within the groove and is adapted to be engaged by the 40 shoulder 63. The arm 39 carries a roller at its lower end which engages in the groove of the cam disk Q and is shifted by the shoulder 62. The arm 35 carries at its upper end a fiber plate 37 to which a switch 45 blade 27^D is attached, while the arm 39 carries at its upper end a fiber plate 38 to which a switch blade 27^U is attached. These switch blades are insulated from the arms and coact with contact members, as will be 50 later stated.
- 55 It will be noted that when the valve G is in the position indicated in Figure 2 and the car has stopped, the arm 36 is in a vertical position and the switch blades 27^D and 27^U are in a vertical contact-engaging position. When the car is ascending, however, the shaft N' will have been given a counter-clockwise movement by the motor which will cause the rotation 60 of the cams in a counter-clockwise direc-
- tion, thus shifting the pivoted arm 36 from its middle position toward the right in Figure 2. This rotation continues until the shoulder 62 strikes the roller on the lower end of the arm 39, when this arm 27^U is 65 shifted from its contact-engaging position (see Figure 6), breaking the circuits, as will be hereafter described. The position of the parts illustrated in Figure 5 is the position taken when the car is descending. The 70 position taken when the car is ascending is illustrated in Figure 6, where the cams are shown as having been turned in a counter-clockwise direction, causing the shifting of the limit switch arm 36 to the right from 75 its median position and causing the switch blade 30 to shift away from its corresponding contacts, while the switch blade 35 remains in engagement with its contacts. This shifting of the arms 35 and 39 is accomplished 80 by the engagement of these arms by the shoulders 63 and 62 respectively.
- The car C' is provided with a casing or box having therein a plurality of switch buttons such as are used in automatic electric elevators, there being a button to be depressed in order to bring the car to a stop and a series of buttons, one for each floor. I will assume that there are three floors and that there are, therefore, three 90 switch buttons designated respectively T', T², and T³, T' being for the first floor, T² for the second floor and T³ for the third floor, and that there is a stop button T⁴ whereby the elevator may be brought to a 95 stop if it is desired to change the direction of the elevator before reaching a floor, the elevator being brought to a stop by the activation of this button and then a button pressed to cause the change in direction of the 100 car and its movement to the floor desired.
- 100 It will be understood, generally speaking, that when a person enters the elevator at the first floor and desires to go to the third, he will, after closing the doors of the elevator, press the button for the third floor. This will cause, through mechanism to be hereafter stated, the closing of a circuit 105 through the motor and the motor will shift the valve G downward. The motor 110 will be brought automatically to a stop as soon as the valve has been shifted sufficiently to cause the supply pipe F³ to be connected to the pipe E and the water will pass into the cylinder and beneath the 115 plunger and the elevator will move upward until the third floor is reached and at this 120 third floor electrical mechanism will operate to again actuate the motor to cause it to shift the valve G to its neutral or holding position so as to bring the car to a stop. If the car is left at the third floor and a party on the second floor desires the 125 car, for instance, he presses the button at the second floor, whereupon the electrical 130

mechanism is actuated to cause the descent of the car to the second floor, where the car will stop. The operator then presses the button indicating the floor to which he desires to go and this causes the energizing of the motor and causes it to rotate in one direction or the other so that the elevator again moves to the floor desired and comes to a stop, and so on. The specific mechanism whereby this is accomplished is as follows:

The car is controlled (Figure 1) by a pair of magnets designated respectively US and DS (designating up and down), these magnets controlling the direction switches whereby the car is caused to move either up or down by a series of relays 1^R, 2^R and 3^R corresponding to the several floors (there being assumed to be three floors) and a series of holding magnets 1^{HM}, 2^{HM} and 3^{HM} corresponding to the number of floors, the relays closing certain contacts and the holding magnets closing certain contacts, the magnets constituting the direction switches also closing the circuit contacts as will hereafter more fully appear. These several sets of magnets and the contacts controlled thereby are connected to the motor, to the limit switches and the centering switch, to the buttons on the several floors, to the buttons on the car and to the floor stop device as will hereafter appear.

Before explaining the circuits which are controlled by the several switches and magnets, it will be well to explain the mechanical construction of the floor stop device (see Figure 3) which is located in any suitable position and which is driven by a chain X leading from a sprocket on the driving shaft Z supporting the usual overhead sheave. Over this sheave pass the usual cables which are weighted to counterweight the elevator. This being a common construction, it is not believed necessary to illustrate this construction. The chain X passes over a sprocket wheel 66 mounted upon a shaft 66^a, which shaft has thereon a worm 67 and operates in suitable bearings. Mounted upon the worm 67 is a travelling nut 68 which, as the worm rotates, shifts in one direction or the other. This travelling nut carries upon it a longitudinally extending, slotted cam bar 69 formed with a slot 69^a, which slot intermediate its ends is formed with an off-set portion 70. In other words, the two end portions of the slot are off-set with relation to each other and connected by this cam portion 70. This bar slides in guides formed in a frame 69^b, and mounted upon this frame are a series of vertically extending switch rods, designated respectively 71, 89 and 96 and corresponding to the several floors, the switch rod 71 corresponding to the first floor, the switch rod 89 corresponding to the second floor, and the rod 96 corresponding to

the third floor. These rods are urged downward by slot in cam bar 69. The rod 96 carries upon it the contact 97, the rod 89 carries upon it the contact 84, and the rod 71 carries upon it the contact 44.

Disposed below the contact 44 are a pair of contact members 48 and 49, disposed above the contact 97 are a pair of contacts 83 and 90, disposed below the contact 84 are a pair of contacts 82 and 82^a, and disposed above are contacts 85 and 88. When the slotted bar 69 moves to the left in Figure 3 and the cam shoulder 70 strikes the roller carried on the lower end of rod 96, this switch rod rising, carries its contact 97 into engagement with the contacts 83 and 90. When the cam shoulder 70 reaches the roller on the lower end of switch rod 89, this switch rod rises, breaking the connection between the contact 84 and contacts 82 and 82^a and contact 84 making connection with the contacts 85 and 88. When this cam shoulder 70 reaches the roller on the lower end of the switch rod 71, the contact 44 rises, breaking connection between the contacts 44 and contacts 48 and 49. Upon the reverse movement of the cam bar 69, the several switch rods 71, 89 and 96 move downward, the contact 44 electrically connecting the contacts 48 and 49, the contact 84 electrically connecting the two contacts 82 and 82^a and the contact 97 breaking engagement with the contacts 83 and 90.

The action of this floor stop mechanism in stopping the car at a predetermined floor will appear hereafter. The switch Y' constitutes the means whereby the power from the source of energy may be communicated to the apparatus through the switch poles 1 and 27. (Figure 1).

The connections between the several switches, buttons, motor, etc., will most readily appear by a description of the operation of the various parts. As before explained, the mechanism which I have illustrated in the accompanying drawings is for a full automatic electric hydraulic control, wherein if the car is at one floor it may be caused to move to any other floor by the closing of a button switch at that floor, the car moving to the floor specified and stopping automatically at this floor, and wherein the car may then be caused to move to any floor desired by a person within the car by pressing the proper car button, whereupon the car will move automatically to the floor desired and stop at this floor.

Assuming now that the car is at the third floor and a person on the first floor wishes the car, then he presses the first floor button 90. (Figure 4). The current then comes from the negative side 27. The current flows from 27 by way of wire a to binding post 8^b on the switch board, then by way of wire b through the first, second and third floor door lock switches 2, 3 and 4, and thence

5 by conductor c to binding post 5 at the cable head in the elevator well through the operating cable by wire c' to the car door switch 6, thence by wire c^2 to one side of stop button 7 in the button box on the car, and through the stop button 7 to binding post 8 which is common to all the buttons.

10 The car door switch may be of any suitable character and simply consists of a switch which, when the door is closed, completes the circuit between wire c' and c^2 but which, when the door is open, automatically breaks this circuit. I have illustrated a pivoted member 6^a having a contact 6^b 15 which, when the door is closed, bridges the gap between the contacts 6^c and 6^d. I do not wish to be limited, however, to any particular form of the car door switch.

20 The button box on the car is fed by a copper plate 93 to which the binding post 8 is fastened. The several floor buttons t' , t^2 and t^3 are fed from binding post 8 which is connected to a wire d which extends to the binding post 9 in cable head and by a wire 25 d' which extends from the binding post 9 to a wire 10 which is common to the first, second and third floor push buttons 90, 91 and 92. The current comes down on the common wire 10 to the first floor button 90, 30 which has been closed, and from thence by wire e to binding post 12^B on switch board Y, thence by wire e' to relay 1^R, thence by wire e^2 to binding post 4^B, thence by wire e^3 to the retarding switch contact 13 on 35 the switch blade 30 on the limit switch and from the contact 12 by wire f to binding post 2^B which is connected to the positive side 1 of the line by a wire f' . This completes the circuit through the source of current and 1^R relay, which is the first floor relay. The energizing of this relay causes the contact 14 to electrically engage the contact 15 and the contact 16 to electrically engage the contact 17. The current passes 40 from the negative side 27 of the line by means of wires a , b , c , c' , c^2 , d and d' to the wire 10, as before stated, but from this common wire 10, however, a wire g leads to binding post 23^B. From this binding post a wire 45 g' leads to a wire g^2 which is connected to the contact 16 of 1^R relay, contact 20 of 2^R relay, and contact 24 of 3^R relay.

Assuming, therefore, that the 1^R relay is energized and the contact 16 is in engagement 50 with the contact 17, then the current passes from the wire g^2 by way of contacts 16 and 17 to wire g^3 . The current then passes along the wire g^3 to binding post 28, thence through holding magnet 1^{hm} to binding post 55 26, from this binding post by way of wire g^4 to contact 15, thence to contact 14 on wire f' and from wire f' back to the positive side 1 of the line, thus energizing the first floor holding magnet 1^{hm}. The energizing 60 of the holding magnet 1^{hm} causes contact 40

to electrically engage contact 43 and also causes contact 31 to electrically engage contact 32. Then the current comes from the negative side 27 of the line by way of wire a to the binding post 8^B and thence by wire h 70 to the current travels to a conductor h' and by wires h^2 to contacts 28^D and 28^U on each side of the limit switch in Figure 2.

As the car is intended to descend, it will cause the current to pass from the contact 75 28^D to the contact 26^D through the switch blade 27^D, and from this contact 26^D the current passes by a wire h^3 to a binding post 11^B on the switch board. From here the current passes by wire h^4 to binding post 65, 80 through the down direction switch DS to binding post 12, thence by wire i to binding post 22^B, thence by wire i' and wire i^2 to contact 49 which coacts with the first floor stop switch rod 71. The switch rod 71 being lowered, as illustrated in Figure 3, the current passes from 49 to 44 and from thence by wire i^3 , passes to binding post 18^B, thence by wire i^4 to contact 43 on #1 holding magnet. Inasmuch as the switch blade 40 engages this contact 43, it allows the current to pass from contact 43 to switch blade 40 which is connected by the wire i^5 to wire f' , which in turn is connected to the positive side of the line at 1. This energizes the 95 down direction switch and causes the motor to rotate, as will be now stated.

The energizing of the down direction switch DS causes an electrical engagement 100 between the contacts 1^M and 2^M and contacts 8^M and 7^M, the energizing of the up direction switch causing the closing of the contacts 1^M to 13^M and of 15^M to 14^M. The down direction switch being energized, closes the circuit through the motor as follows: The 105 current comes from the positive side 1 of the line by the wire j to the contact 1^M, the wire j being connected to the contact 1^M of the down direction switch and the contact 1^M of the up direction switch. The down direction 110 switch being closed, current passes from 1^M to 2^M and from 2^M through the switch to the contact 3^M and from thence by wire j' to contact 3^B, thence by wire j^2 to binding post 4^M on the motor, through the armature thereof, back to binding post 5^M on the motor by wire j^3 to binding post 1^B on the switch board and thence to contact 6^M on the down direction switch by means of wires j^4 and j^5 , 115 j^5 being connected to the contact 6^M of the up direction switch and the down direction switch both. From 6^M on the down direction switch the conductor leads to the contact 7^M which, being in electrical engagement 120 with 8^M, causes the current to pass through 8^M to wire k to the binding post 9^B, from binding post 9^B by wire k' to contact 9^M on the down side of the limit switch, through the switch blade 27^D, to contact 28^P, thence by wires k^2 and k' and 125 130

wire h to binding post 8^B , from thence by wire a back to the negative side 27 of the line, thereby energizing the armature circuit of the motor. One side of the shunt field of the motor is fed from the positive side 1 of the line by way of wire j to the contact 1^M , thence to the contact 2^M , from thence to the contact 12^M for the down direction switch DS, thence by wire e and wire l' to binding post 5^B on the switch board, thence by wire l^2 to binding post 11^M on the motor, through the shunt field to binding post 10^M on the motor, from thence by wires l^3 and h' and h to binding post 8^B , thence by wire a to 27 on the negative side of the line. Thus the motor is caused to rotate in a direction to cause the upward movement of the arm N^2 and the upward movement of the valve stem G to thereby relieve the pressure of water beneath the plunger B and permit the plunger and the car to descend. The rotation of the motor revolves worm I' , which causes the worm gear N to revolve and this moves the arm N^2 which is connected to valve stem through the connecting rod N^3 , causing the valve stem G to move upward and causing the cup packings or pistons H , H' and H^2 to move upward until the packing H^2 moves by the port leading to pipe E , and this allows the water to be discharged from the cylinder through the circuit breaker valve I and allows the car to descend.

When the shaft N' revolves in a clockwise direction, it also revolves cams O , P and Q in the same direction. The instant that cam O moves toward the right from the position shown in Figure 2 to the position shown in Figure 5, it moves the lower end of the arm 36 to the right, causing the switch blade 30 to move to the left to the position shown in Figure 5, connecting the contacts 11^F and RC . This switch blade moves against the action of the centering spring 47 which tends to urge the switch blade back to its normal or central position where it connects the contacts 12 and 13. While the cam O is moving to the right, the cam P also moves to the right in Figure 2 and the shoulder on this cam further engages the lower end of the lever 35 of the down limit switch 27^D and moves this switch blade 27^D to the left, as illustrated in Figure 5, therefore breaking the circuit between contact 28^D and the contact 9^M which is the armature circuit, and between the contacts 28^D and 26^D which are in the down direction switch circuit, releasing the down direction magnet of the down direction switch DS, also breaking the shunt field circuit and causing the motor to stop and leaving limit switches 27^D and 27^U in the position shown in Figure 5. This is the position of the limit switches when the car is descending. Under these circumstances, the contacts 28^U and 16^M are connected and

the contacts 28^U and 26^U are connected. In other words, the limit switch blade 27^U has been left in its initial position, that is the position shown in Figure 2, but the limit switch blade 27^D has been opened. Inasmuch as the contacts 12 and 13 are open, no one can interrupt the use of the car while it is in motion.

In this position of the parts, the holding magnet for the first floor 1^{HM} is still being held energized, this magnet getting its current, as before, from the negative side 27 of the line, through the car switch buttons and the car door switch, and back to binding post 23^B . The #1 holding magnet 1^{HM} from this point on, however, gets its current as follows: The wire m connects with the wire g' at 94 and extends to contact 32. As the contact 31 is engaged with 32 through the energizing of 1^{HM} , current flows from 32 to 31 and from 31 to post 28, through 1^{HM} to the point 26 on wire g^4 , thence by wire m' to binding post 15^B , thence by wire m^2 to contact 48 of the floor stop switch for the first floor, to contact 44, by way of wire i^2 to binding post 18^B and thence by wire i^4 to contact 43, thence to the switch blade 40 and from the switch blade by wire i^5 and wire f' to the positive side 1 of the line. This completes the circuit through the holding magnet for the first floor 1^{HM} and keeps this magnet energized.

As the car descends from the third floor toward the first floor, the worm 67 is caused to revolve by the sprocket wheel 66 which, as before remarked, is connected to the overhead sheave shaft, and as the worm 67 revolves it moves the travelling cam bar 69 to the left through the nut 68, and when the cam shoulder or off-set 70 engages roller 71 of the first floor stop switch 44, it shifts the switch bar 44 upward, breaking contact between 48 and 44, which releases the holding magnet 1^{HM} . This causes the contacts 31 and 32 to separate and shifts the switch blade 40 from its engagement with contact 43 into engagement with the contact 72. This causes the re-energizing of the motor circuit so as to cause the motor to rotate in a direction reverse to that first taken to thereby cause the descent of the valve stem G to carry the cups H' and H^2 into the position shown in Figure 2 to thereby cause the stoppage of the car. The de-energizing of the holding magnet 1^{HM} causes the disengagement of blade 40 from the contact 43, and breaks contact between the contacts 31 and 32, and then the current comes from the negative side 27 of the line by wire a to the binding post 8^B down by wire h and wire h' to the limit switch contact 28^U , and thence by the switch blade 27^U to the contact 26^U , thence by wire n to binding post 10^B , thence by wire n' , to binding post 76, which is one side of the up 130

direction switch US, through the coil of the up direction electro-magnet of this switch to binding post 11, and thence by wire n^2 to binding post 21^b, thence by wire 5 o to contact 11^e coacting with the centering switch blade 30. The centering switch 30 being closed, that is in engagement with the contact 11^e, the current passes from 11^e to contact RC, from thence by wire o' common to both contacts RC to binding post 6^b, from thence by wire o^2 to contact 75, thence to the contact member 74 of holding magnet 3^{HM}, then by wire o^3 to contact 73 of the holding magnet 2^{HM}, thence to the contact 15 42 thereof, thence to wire o^4 to contact 72, thence to 40 of holding magnet 1^{HM}, then by wire i^5 to wire f' , thence by wire j to the positive side of the line at 1, thus completing the circuit through the up direction 20 switch US, which causes the closing of the contacts 1^M and 13^M, 15^M and 14^M by means of the wires heretofore described, closing the circuit through the up switch and causing the motor to revolve in the opposite 25 direction to that in which it originally did, thereby reversing the operation and moving the valve stem G downward until the cup H² passes pipe E, closing this pipe and stopping the car.

30 When the pipe is closed, the cam O has returned to its normal position and in its action of returning to its normal position it moves the centering switch blade 30 from the position shown in Figure 5 to its middle 35 position, thereby breaking the circuit between 11^e and RC, which releases the magnet of the up direction switch US, stopping the motor also. As the centering switch blade 30 returns to its center, it closes contacts 12 and 13 and the limit switch blade 26^d electrically engages contacts 28^d, 9^M and 26^d of the limit switch, therefore leaving the car ready for operation from any floor at any time and in the position shown in 40 Figure 2. As the car descends, the cam or off-set 70 of the floor stop cam bar 69 goes by the switch rods 96 and 89 and throws the switches 97 and 84 so as to allow the car to be sent to either landing.

45 In order for a person within the car to send the car up to the second floor from a lower floor, as for instance the first floor, the second floor button T² on the car is pressed. Then the current comes from contact plate 50 93, which gets its current, as previously mentioned, through the door switches, door button, etc., and so from the negative side 27 of the line. The current flows from contact plate 93 through the operating cable to the 55 binding post 77 by wire p , thence by wire p' to binding post 13^b on the switch board, thence by wire p^2 to and through the second floor relay 2^R to wire p^3 thence by wire p^2 to binding post 4^b, from 60 thence to the retarding switch contacts 12 and 13 by wire e^3 , thence by wire f to binding post 2^R, thence by wire f' to the positive side 1 (one) of the line. Thus the second floor relay is energized. This closes contact 18 to contact 19 and 20 to contact 21. The circuit 65 from the negative side of the line to the common wire 10 has been previously traced. From this common wire 10 the wire g leads to the binding post 23^b, from this binding post lead the wires g' and g^2 to contact 20, and the 70 contacts 20 and 21 being closed allows the current to pass from 20 and 21 by wire g^4 to 75 79, which is one side of the second floor holding magnet 2^{HM}. The current passes through this second floor holding magnet to 80 the point 78 and thence by wire g' to the contact 19, from the contact 19 to 18 and from the contact 18 by wire f' to the positive side 1 of the line. This completes the circuit through the second floor holding magnet 2^{HM}, 85 shifting the contact 42 into engagement with the contact 80 and closing contacts 86 and 87. Then the current comes from the negative side 27 of the line to binding post 8^b by way of wire a , and from thence by wire h 90 and wire h' to contact 28^U on the up side of the limit switch. From 28^U the current passes to 26^U via switch blade 27^U and from 26^U by wire n to binding post 10^b on the switch board, thence by wire n' to binding 95 post 76 of the up direction switch US through the magnet of this switch to binding post 11, from thence by wire n^2 to binding post 21^b and from thence by wires o and o^3 to contact 88 on the floor stop device, this 100 being the second floor contact. At this time the switch is closed, having been shifted upward by the cam bar 69 on its leftward movement, and current passes from contact 88 to the contact 84, thence the current flows 105 by wire q^2 to binding post 19^b, from thence by wire q^3 to contact 80 of the second floor holding magnet 2^{HM}. The switch 42 being closed or in engagement with this contact 80, the current passes to 42 and from thence 110 by wire o^4 to contact 72, through switch 40 and by wire i^5 to wire f' to the positive side 1 of the line. This closes the circuit through the up direction switch, as previously described, and thus by closing the contacts 1^M and 13^M and 15^M and 14^M, closes the circuit 115 through the motor, operating the valve stem G through the worm gear and worm as previously described, causing the valve stem to move down until the packing h' passes by 120 the pipe E, opening the same and establishing communication between the supply pipe F² and pipe E, the pressure of water passing into the cylinder forcing the car to ascend. The moment the cam O revolves to the left, 125 as illustrated in Figure 6, it moves the lower end of the centering switch 30 and causes the switch blade to move toward the right, closing contacts 12^e and RC. At the same time the shoulder 62 engages the lower end 130

of the limit switch 27^U which moves this switch blade 27^U to the right, thereby breaking the circuit between 28^U and 16^M, which is the armature circuit as previously described, 5 and 28^U and 26^U, which is the up direction switch circuit, releasing the up direction switch (which opens shunt field) and stopping the motor, as in Figure 6, which figure shows the position of the limit switches when car is 10 ascending.

Inasmuch as the switch blade 30 has left the contacts 12 and 13, it will be obvious that nobody can interrupt the use of the car while it is in motion. As the car ascends, the 15 worm 67 revolves and the travelling nut 68 moves the cam bar 69 toward the right. When the cam shoulder or off-set 70 engages the roller on the second floor switch 89, it draws the switch 89 downward, breaking 20 engagement between contact 84 and contact 35, which releases #2 holding magnet 2^{HM}, which in turn breaks engagement between the contacts 86 and 87 and at the same time closes switch blade 42 to contact 73. This 25 causes the operation of the down direction switch on switch board, causing the motor to revolve in the opposite direction, thereby reversing the operation and moving valve stem G upward until cup H' passes pipe E, 30 closing the same and stopping car.

In order to accomplish this, the current comes from the negative side 27 of the line to binding post 8^B on the switch board by way of wire *a*, from 8^B by wires *h*, *h'* and 35 *h*² to contact 28^D on the down side of the limit switch, and thence to 26^D, from thence by wire *h*³ to binding post 11^B, thence by wire *h*⁴ to the binding post 65 of the down direction switch DS, through the magnet 40 of this switch to binding post 12, thence to binding post 2^B by way of wire *i*, from thence by wire *i'* and *r* to contact 12^R. The centering switch blade 30 being closed, as 45 illustrated in Figure 6, current passes from 12^R to RC and from thence by wire *o'* to binding post 6^B and thence by wire *o*² to contact 75 of the third floor holding magnet 3^{HM}, thence to the contact 74, thence by wire 50 *o*³ to contact 73, thence to contact 42, thence by wire *o*⁴ to contact 72, thence to contact 40, and thence by way of wire *i*⁵ and *f'* back to the positive side of the line 1. This 55 operates to down direction switch D, as previously explained, and moves valve stem G to its stop position, stopping the car and, of course, acting to return the limit switch to its middle or stop position, as shown in Figure 2.

I have heretofore described the means 60 whereby a person on the first floor may secure, by pressing a button, a return of the car from an upper floor to the first floor, and I have described the means whereby a person within the car by pushing the proper button 65 may cause the car to move from the first

floor to the second floor. It will be obvious, however, that the same operation is performed only with a different button when it is desired by a person on any one floor to cause the car to move to that floor, or when 70 it is desired by a person within the car to cause the car to move to any desired floor. It is not believed necessary to trace all of the circuits which are caused to close or open under these circumstances, this being obvious to those skilled in the art. 75

The holding switches are shown diagrammatically in Figure 1, but in Figures 9 and 10, I show detailed views of the holding switch so as to illustrate its exact construction. In these figures V designates the frame supporting one of the holding magnets, as for instance the magnet 1^{HM}. Pivoted upon the frame is a lever V' carrying a screw V² coacting with the magnet 1^{HM}. 80 This screw carries the contact 31 which coacts with the contact 32. The opposite end of the lever carries upon it a cross bar constituting the contact 40, this cross bar, when the magnet is energized, engaging the contact 43, and when the magnet is de-energized engaging the contact 72, the armature being carried away from the pole of the magnet when the magnet is de-energized by means of a spring, weight or any other suitable device of this character. The contacts 14 and 16 are mounted upon a like lever to that illustrated in Figure 9 so that upon an energizing of the relay magnet 1^R, the contacts 14 and 16 will be brought into engagement with 100 the contacts 15 and 17. It is not believed necessary to illustrate this particular circuit closing device, as it will be obvious.

The direction switches are constructed in accordance with Figures 11 and 12, which 105 illustrate the direction switch DS. In these figures, W designates the magnet of the direction switch, and W' an armature which is pivoted upon the frame of the magnet and which carries the contacts 2^M and 7^M. Projecting laterally from the armature blade W' is the contact W². When the magnet W is energized, it draws the armature downward and the contact 2^M engages the contact 1^M, while the contact 7^M engages the contact 8^M. At the same time the contact W² engages the contact 12^M, this contact being supported by a spring W³ so that this contact is closed just before the contacts 2^M and 7^M engage the contacts 1^M and 8^M. Of course, the 115 armature W' is urged upward by a spring or any other suitable means to that end. 120

With regard to the functioning of the direction switches US and DS, it is pointed out that in the neutral or zero position of 125 the shaft N' and the valve, that is the holding position when the elevator is at rest, the circuit is completed through both the limit switch blades 27^U and 27^D but not through the centering switch blade 30 but 130

this circuit is broken between the contacts controlled by the direction switches. When the circuit is closed through one direction switch magnet, as by the pressing inward of 5 the proper floor button or the selected car button, the current travels in one direction through the motor and through one of the limit switches and the motor is operated in one direction to shift the valve into its selected position from its holding position. Then when the valve is fully shifted, the circuit is automatically broken through the limit switch blade which has been in circuit with the motor and the reverse circuit is partially completed by the centering switch 30 10 engaging the contact 11^r with the contact RC or the contact 12^r with the contact RC. This circuit, however, is only partially completed as the circuit simply remains broken 15 or interrupted at the floor switch for the particular floor at which the car is to stop. Thus when the proper floor switch is closed, current reverses through the motor until the valve is in its held or stop position, when 20 current is again broken automatically by the reason of the centering switch blade 30 moving to its middle position under the action of the rotating cam O.

It will be seen that when one of the direction magnets is energized and the contacts closed, current passes in one direction through the armature and shunt circuits and that when the other direction magnet is closed, the current passes in the opposite direction through the armature and shunt circuits of the motor. Thus the direction switches US and DS constitute reversing switches and the centering switch constitutes means when one of the direction switches is 35 energized of putting the circuit of the other direction switch in condition to be energized.

From Figures 1 and 2, it will be seen that the magnet 50 is connected in circuit by means of the wires s and s' with the positive 40 and negative poles of the main power switch Y'. Thus the magnet 50 is at all times energized unless a fuse should blow out or the power should be cut off in some way on the main line. These wires s and s' are also connected, as will be seen from Figure 1, to the wires j and a respectively so that if the current is interrupted from any cause the car will stop immediately.

Inasmuch as the counter-weighted cables 45 which assist in supporting the elevator and pass over the sheaves on the shaft Z tend to slip, it is necessary that the sheave on shaft Z be driven by friction and not through a positive engagement with the shaft Z and it is necessary to provide the limit nuts 67^a 50 on the screw-shaft 67. These limit nuts also set the shaft at each end of the travel of member 68, thereby taking care of slippage of the counter-weighted cables. This construction forms no part of my present inven-

tion but is merely stated so as to show that means may be readily provided for preventing the slippage of the counter-weighted cables from affecting in any way the floor stop mechanism.

70

I claim:

1. A hydraulic elevator including a car and hydraulically actuated means for shifting the car, of a valve controlling the passage of water through said means, said valve 75 having an inlet position, an outlet position, and an intermediate holding position, a reversible electric motor, operative connections between the motor and the valve whereby the valve may be positively shifted in either direction to its various positions by a movement of the motor in one direction or the other, selective means for actuating the motor to cause a rotation of the armature shaft in either direction to thereby shift the valve 80 toward or from its intermediate holding position and toward or from either of its other positions, and means for automatically stopping the motor when the valve has moved a predetermined distance in one direction 85 and has reached its inlet, outlet or holding position.

2. A hydraulic elevator including a car, hydraulically actuated means for shifting the car, a valve controlling the passage of 95 water to said means, said valve having an inlet position, an outlet position and an intermediate holding position, a reversible electric motor operatively connected to the valve to shift it, means for actuating the 100 motor to cause a rotation of the armature shaft in either direction to shift the valve toward or from its intermediate holding position, and means for automatically stopping the motor when the valve has moved a predetermined position in one direction and has 105 reached its inlet or holding position, including an oscillatable member driven by said motor in a direction corresponding to the direction of movement of the motor, a switch 110 blade normally held in a circuit closing position, and a member driven by the motor and operatively engaging said switch blade to shift it from its circuit closing position when the motor has rotated a predetermined 115 amount.

3. A hydraulic elevator including a car, hydraulically actuated means for shifting the car, a valve controlling the passage of 120 water to said means, said valve having an inlet position, an outlet position and an intermediate holding position, a reversible electric motor, operative connections between the motor and the valve, means for actuating the motor to cause the rotation of 125 the armature shaft in either direction to or from its holding position including a pair of switch blades disposed in a normally interrupted circuit with a source of energy and said motor, one of said switch blades 130

partly closing a circuit through the motor and the source of energy in one direction, the other of said switch blades partly closing a circuit through the motor and the source of energy in the other direction, manually controlled means for closing the circuit through either one of said switch blades to thereby cause the rotation of the motor in either direction, and means for 10 automatically shifting the switch blade through which the circuit is closed from its circuit closing position and thus stopping the motor when the valve has moved a predetermined distance in one direction and has 15 reached its inlet, outlet or holding position comprising an oscillatable member driven in a direction to correspond to the direction of movement of the motor, said member when shifted in one or the other direction a 20 predetermined amount operatively engaging the switch blade through which the circuit is closed and causing the opening of said switch blade.

4. A hydraulic elevator including a car, 25 hydraulically actuated means for shifting the car, a valve controlling the passage of water to said means, said valve having an inlet position, an outlet position and an intermediate holding position, a reversible 30 electric motor, operative connections between the motor and the valve, means for actuating the motor to cause the rotation of the armature shaft in either direction to or from its holding position including a pair of switch blades disposed in a normally interrupted circuit with a source of energy and said motor, one of said switch blades closing a circuit through the motor and the source of energy 35 in one direction, the other of said switch blades closing a circuit through the motor and the source of energy in the other direction, manually controlled means for closing the circuit through either one of said switch blades to thereby cause the rotation of the motor in either direction, and means for automatically shifting the switch blade through which the circuit is closed from its circuit closing position and thus stopping the motor when the valve has moved a predetermined distance in one direction and has 40 reached its inlet, outlet or holding position comprising an oscillatable member driven in a direction to correspond to the direction of movement of the motor, a shaft upon which said member is mounted, a worm wheel carried by said shaft, a worm actuated by the motor and engaging said worm wheel, said member having a pair of shoulders coacting respectively with the respective switch blades whereby as the motor 45 is rotated in one direction said member will be rotated to carry its shoulder into engagement with the switch blade through which the circuit is closed to cause the switch blade to open and thereby break the circuit through the motor.

5. A hydraulic elevator including a car, hydraulically actuated means for shifting the car, a valve controlling the passage of water to said means, said valve being longitudinally shiftable and having an inlet position, an outlet position and an intermediate holding position, a reversible electric motor, a worm carried thereon, a shaft, a worm wheel mounted upon the shaft and engaged by said worm, an arm on the shaft operatively connected to the valve to shift it as the worm wheel is oscillated, and means for actuating the motor to cause a rotation of the armature shaft in either direction to 110 shift the valve toward or from its intermediate holding position including a pair of switch blades contacts with which said blades normally engage, said contacts being electrically connected to the motor and to 115 the source of current, one pair of contacts, when the circuit is closed therethrough, acting to cause the current to flow in one direction through the motor and the other pair of contacts, when the circuit is closed there- 120

6. A hydraulic elevator including a car, hydraulically actuated means for shifting

the car, a valve controlling the passage of water to said means, said valve having an inlet position, an outlet position and an intermediate holding position, a reversible electric motor, operative connections between the motor and the valve, means for actuating the motor to cause the rotation of the armature shaft in either direction to or from its holding position including a pair of switch blades disposed in a normally interrupted circuit with a source of energy and said motor, one of said switch blades closing a circuit through the motor and the source of energy in one direction, the other of said switch blades closing a circuit 70 through the motor and the source of energy in the other direction, manually controlled means for closing the circuit through either one of said switch blades to thereby cause the rotation of the motor in either direction, and means for automatically shifting the switch blade through which the circuit is closed from its circuit closing position and thus stopping the motor when the valve has moved a predetermined distance in one direction and has 75 reached its inlet, outlet or holding position comprising an oscillatable member driven in a direction to correspond to the direction of movement of the motor, a shaft upon which said member is mounted, a worm wheel carried by said shaft, a worm actuated by the motor and engaging said worm wheel, said member having a pair of shoulders coacting respectively with the respective switch blades whereby as the motor 80 is rotated in one direction said member will be rotated to carry its shoulder into engagement with the switch blade through which the circuit is closed to cause the switch blade to open and thereby break the circuit 85 through the motor.

6. A hydraulic elevator including a car, hydraulically actuated means for shifting the car, a valve controlling the passage of water to said means, said valve being longitudinally shiftable and having an inlet position, an outlet position and an intermediate holding position, a reversible electric motor, a worm carried thereon, a shaft, a worm wheel mounted upon the shaft and engaged by said worm, an arm on the shaft operatively connected to the valve to shift it as the worm wheel is oscillated, and means for actuating the motor to cause a rotation of the armature shaft in either direction to 110 shift the valve toward or from its intermediate holding position including a pair of switch blades contacts with which said blades normally engage, said contacts being electrically connected to the motor and to 115 the source of current, one pair of contacts, when the circuit is closed therethrough, acting to cause the current to flow in one direction through the motor and the other pair of contacts, when the circuit is closed there- 120

- through, acting to cause the current to flow in the other direction through the motor, means normally holding both of said switch blades in engagement with their respective 5 contacts, means for closing a circuit through either one of said switch blades and the source of current to thereby cause the actuation of the motor in one direction or the other, and means for automatically shifting 10 said active switch blade from its contact engaging position to break the circuit when the valve has reached a predetermined position comprising a rotatable member having spaced shoulders, said shoulders corresponding 15 to but being normally spaced from operative engagement with the switch blades but upon a rotation of the shaft in one or the other direction operatively engaging the switch blade through which the current is 20 passing to shift it out of engagement with its contacts to thereby break the circuit through the motor.
7. A hydraulic elevator including a car, hydraulically actuated means for shifting 25 the car, a valve controlling the passage of water to said means, said valve being longitudinally shiftable and having an inlet position, an outlet position and an intermediate holding position, a reversible electric motor, 30 a worm carried thereon, a shaft, a worm wheel mounted upon the shaft and engaged by said worm, an arm on the shaft operatively connected to the valve to shift it as the worm wheel is oscillated, means for 35 actuating the motor to cause a rotation of the armature shaft in either direction to shift the valve toward or from its intermediate holding position including a pair of switch blades, contacts with which said 40 blades normally engage, said contacts being electrically connected to the motor and to the source of current, one pair of contacts, when the circuit is closed therethrough, acting to cause the current to flow in one direction 45 through the motor and the other pair of contacts, when the circuit is closed therethrough, acting to cause the current to flow in the other direction through the motor, means normally holding both of said switch 50 blades in engagement with their respective contacts, means for closing a circuit through either one of said switch blades and the source of current to thereby cause the actuation of the motor in one direction or the 55 other, and means for automatically shifting said active switch blade from its contact engaging position to break the circuit when the valve has reached a predetermined position comprising a rotatable member, said 60 member including two sections adjustable with relation to each other and each of these sections having a shoulder, the respective shoulders coacting with the respective switch blades but being normally spaced therefrom, 65 a rotation of said shaft and member from an intermediate position causing one of said shoulders to engage the active switch blade and shift it from its contact engaging position after a predetermined rotation of the member to thereby break the circuit through 70 said motor.
8. A hydraulic elevator including a car and hydraulically actuated means for shifting the car, of a valve controlling the passage of water through said means, said valve 75 having an inlet position, an outlet position and an intermediate holding position, a reversible electric motor, operative connections between the motor and the valve whereby it may be shifted to its several positions, 80 means for actuating the motor to cause a rotation of the armature shaft in either direction to shift the valve to or from its holding position and including two sets of contacts, a pair of switch blades coacting with 85 the respective sets of contacts, means normally urging said switch blades into engagement with said contacts, said contacts being thereby connected in an interrupted circuit with the motor and a source of energy, 90 means for closing a circuit through the source of energy and either set of said contacts and the corresponding switch blade, means for breaking the circuit through the active switch blade after the valve has moved to its 95 selected position from an intermediate closing position including a member oscillated by the motor and having a pair of shoulders normally engaged spaced from but adapted to engage with one or the other of the switch 100 blades to shift the active switch blade out of its contact engaging position after a predetermined rotation of the motor and a predetermined movement of the valve, and means actuated by the movement of the member 105 to its switch blade shifting position automatically closing at one point a reverse circuit through the motor, means for completely closing the circuit through the last named means to cause the motor to revolve 110 in the opposite direction, the reverse rotation of the motor causing the last named circuit closing means to break the circuit through the motor after the motor has travelled in a reverse direction a predetermined 115 amount.
9. In a hydraulic elevator, a controlling valve therefor operable from or to an intermediate holding position to or from an inlet position or an outlet position, a reversible 120 electric motor operatively connected to the valve to positively shift from or to its intermediate position by a rotation of the motor in one direction or the other, manually controlled, electrically operated selective 125 means causing the current to flow in one or the other direction through the motor to thereby actuate the motor in one or the other direction, and motor operated means automatically breaking the circuit through the 130

motor after the motor has been started and a predetermined number of revolutions have been made.

10. In a hydraulic elevator, a controlling valve therefor, a reversible electric motor operatively connected to the valve to shift it, said valve having an inlet position, an outlet position and an intermediate holding position, manually operable selective means 10 for directing current through the motor in a direction to shift the valve from its intermediate holding position toward its inlet or its outlet position, means acting to automatically break this circuit through the motor when the valve has reached its inlet or outlet positions, means to direct current through the motor in a direction to cause the valve to move to its intermediate or holding position when the elevator has reached a 20 predetermined height, and means acting automatically to break the current through the motor when the valve has again reached its intermediate and holding position.

11. In a hydraulic elevator, a controlling valve therefor, said valve having an inlet, outlet and intermediate holding position, a constant speed reversible electric motor operatively connected to the valve to shift it to its several positions, means for actuating 30 the motor to cause a rotation of the armature shaft in either direction to shift the valve to or from its holding position and including two sets of contacts, a pair of switch blades coacting with the respective sets of 35 contacts, means normally urging said switch blades into engagement with said contacts, said contacts being thereby connected in an interrupted circuit with the motor and a source of energy, means for closing a circuit 40 through the source of energy and either set of said contacts and the corresponding switch blade to thereby actuate the motor, means for breaking the circuit through the active switch blade after the motor has operated and the valve has moved to its selected position from an intermediate closing 45 position including a member oscillated by the motor, said member including two sections adjustable with relation to each other and each of these sections having a shoulder, the respective shoulders coacting with the 50 respective switch blades but being normally spaced therefrom, a rotation of said shaft and member from an intermediate position causing one of said shoulders to engage the active switch blade and shift it from its contact engaging position after a predetermined rotation of the member to thereby break the circuit through said motor, and 55 means actuated by the movement of the member to its switch blade shifting position automatically closing at one point a reverse circuit through the motor and including a member mounted for oscillation on said first 60

named members, and a switch blade oscillated by said member, and means for completely closing the circuit through the last named means to cause the motor to revolve in the opposite direction, the reverse rotation of the motor causing the last named circuit closing means to break a circuit through the motor after the motor has moved in the reverse direction a predetermined amount and the valve has returned to its holding position. 75

12. In a hydraulic elevator, a constant speed reversible motor, circuit controlling means driven by the motor and reversible with the motor and including a member having two spaced shoulders, switch blades, 80 contacts therefor with which the switch blades are normally engaged, and means on said member operatively engaging one of said switch blades after a predetermined rotation of the motor upon a rotation of the member in one direction to shift the switch blade out of engagement with its contacts and adapted to operatively engage the other switch blade upon the reverse movement of the member after a predetermined rotation 85 of the motor to shift the other blade out of engagement with its contacts.

13. In a hydraulic elevator, a constant speed reversible motor, a member driven thereby and reversible with the motor, a pivoted switch blade operatively engaged with the member to be oscillated thereby upon an oscillation of the member in either direction, oppositely disposed pairs of contacts with which said switch blade is adapted to engage, 100 switch blades disposed on either side of the first named switch blade, contacts coacting therewith, and means for urging said last named switch blades into engagement with their respective contacts, the oscillatable member having shoulders adapted to operatively engage with one or the other of the switch blades as the member oscillates in one or the other direction to the action of the motor and for a predetermined rotation of 105 the motor to thereby break the circuit through said switch blades. 110

14. In a hydraulic elevator, a constant speed reversible electric motor having an armature shaft, a worm driven thereby, a disk-like member mounted for rotation and operatively engaging said worm whereby the disk-like member may be shifted in reverse directions as the motor is rotated in reverse directions, the disk-like member being 115 formed in three sections adjustable with relation to each other, a pivoted switch blade having one end engaged with one of said sections and oscillated by an oscillation of the member in one direction or the other, 120 oppositely disposed contacts with which the switch blade is adapted to be engaged, a central pair of contacts with which said 125

- switch blade is in normal engagement when the motor is stationary, a pair of switch blades pivoted on each side of the first named switch blade, contacts with which 5 said switch blades are adapted to engage, and means for urging the switch blade into engagement with the contacts, one of said sections having thereon a shoulder adapted to engage with the adjacent switch 10 blade to shift it out of engagement with its contacts when the member is rotated in one direction and after a predetermined number of revolutions of the motor, and a shoulder on the third section adapted to 15 operatively engage the other of said second named switch blades upon a rotation of the member in the opposite direction consequent upon the reversal of the motor and after a predetermined number of rotations 20 of the motor.
15. In a hydraulic elevator, a main controlling valve having an inlet port and an outlet port, a pipe extending from the main valve to the elevator operating mechanism, 25 manually controlled, electrically operated mechanism for controlling the main valve and including a plurality of circuits, a safety valve shifting the flow of water in the inlet pipe and normally held in an in- 30 operative position but being urged to a closed position, and means for causing the closing of said safety valve upon an interruption occurring in any one of said circuits.
35. 16. In a hydraulic elevator, a main controlling valve casing having an inlet port and an outlet port and having a pipe leading therefrom to the elevator operating mechanism, a safety valve casing in the 40 length of said inlet pipe and between said main valve and the elevator operating mechanism, a safety valve in the casing adapted to close the inlet pipe and urged toward a closed position, and electro-mag- 45 netically operated means for holding the valve raised, said means being rendered inoperative by a breaking of the circuit through the magnet thereof to thereby permit the valve to close under the action of 50 said urging means.
17. In a hydraulic elevator, a main valve casing having an inlet port and a discharge port, a valve operating therein, a pipe leading from the valve casing to the elevator 55 operating apparatus, a safety valve disposed in the length of said pipe and adapted when actuated to prevent the passage of liquid therethrough, said valve being urged to its closed position, electro-magnetically 60 operated means for holding the valve raised, said means being rendered inoperative by a breaking of the circuit through the magnet thereof to thereby permit the valve to close under the action of said urging means, and 65 means for gradually checking the closing of the valve under the action of the urging means.
18. In a hydraulic elevator, an inlet pipe, a normally open valve in the length of said inlet pipe but adapted to be closed to cut off the inlet of water or the outlet of water from the inlet pipe, a lever operatively connected to the valve, a weight carried by the lever and urging the lever to a position to close the valve, a latch adapted to operatively engage the lever to hold it raised, an electro-magnet connected in a normally closed circuit with a source of current, said magnet when energized holding the latch in engagement with the lever and when de- 70 energized releasing the lever, and a dash pot yieldingly resisting the closing of the valve.
19. In a hydraulic elevator, a reversible electric motor, a valve having an inlet position, an outlet position and an intermediate holding position and operatively connected to the motor to be shifted thereby from or to its intermediate holding position, means for directing the current through the motor 75 in a direction to rotate the motor in one or the other direction to shift the valve from its intermediate holding position toward its inlet or its outlet position, means acting automatically to break the circuit through the 80 motor when the valve has reached its inlet or its outlet position, means acting automatically to direct current through the motor in a direction to cause the valve to shift to its intermediate or holding position 85 when the elevator has reached a predetermined position, and means acting automatically to break the current through the 90 motor when the valve has reached its intermediate and holding position.
20. In a hydraulic elevator, a controlling valve having an inlet position, an outlet position and an intermediate holding position, a constant speed reversible electric motor operatively connected to the valve to cause 95 it to shift from its holding position in either direction toward or from its inlet or its outlet positions, selective means for directing current through the motor in either direction including a series of floor switches 100 and a series of car switches mounted within the car, said switches acting as means for directing current through the motor in a direction to shift the valve from its intermediate holding position toward its inlet or 105 its outlet position, means automatically acting to break the circuit through the motor when the valve has reached its inlet or outlet position, said means acting simultaneously to break the circuit through the floor 110 switches, means to direct current through the motor in a direction to cause the valve to move to its intermediate or holding position, and means for automatically breaking the circuit through the motor when the 115
- 120
- 125
- 130

valve has reached its intermediate and holding position and reestablishing an interrupted circuit through said floor switches.

21. A hydraulic elevator including a car, 5 hydraulically actuated means for shifting the valve, a valve controlling the passage of water to said means, said valve having an inlet position, an outlet position and an intermediate holding position, a reversible 10 constant speed electric motor operatively connected to the valve to shift it, a motor circuit interrupted at a plurality of points and adapted to send current through said motor in one direction, a second motor circuit 15 interrupted at a plurality of points and adapted to send a current through the motor in the other direction, a switch blade normally held in a closed circuit position to partly close a circuit through the motor, a 20 second switch blade normally held in an open circuit position and adapted when closed to complete the second circuit referred to, and motor operated means acting automatically to shift the first named blade 25 out of its circuit closing position after the motor has operated a predetermined time and the valve has reached one of its three positions and simultaneously shifting the second named blade into a circuit closing 30 position whereby a circuit may be closed reversely through the motor to cause the reverse actuation thereof.

22. In a hydraulic elevator, a controlling 35 valve therefor shiftable from an intermediate holding position to an inlet position or an outlet position, a constant speed reversible electric motor operatively connected to the valve, manually controlled means for closing a circuit through the motor in either 40 direction to thereby cause the movement of the valve from its holding position in either direction, means for automatically breaking the circuit through the motor when the valve has reached a selected position to 45 thereby permit the inlet or outlet of water and the ascent or descent of the elevator, means automatically closing a circuit through the motor reverse to the circuit last closed when the elevator has reached a pre- 50 determined position to thereby cause the valve to shift to its holding position and stop the elevator, and means breaking the said last named circuit when the valve has reached its holding position.

23. In a hydraulic elevator, a controlling 55 valve therefor shiftable from an intermediate holding position in one direction to an inlet position and in the other direction to an outlet position, a constant speed reversible electric motor operatively connected to the valve, manually controlled means for closing a circuit through the motor in either direction to thereby cause the movement of the valve from its holding position in either

direction to one of its other positions, means 65 controlled by the motor for automatically breaking a circuit through the motor when the valve has reached its selected position to thereby permit the inlet or outlet of water and the ascent or descent of the elevator, 70 an elevator actuated floor stop switch, and means controlled by the elevator for actuating said floor stop switch to cause the closing of a circuit through the motor reverse to the circuit last closed when the elevator has actuated the floor stop switch to thereby cause the valve to shift toward its holding position to thereby stop the elevator, and means breaking the motor circuit last closed when the valve has reached its 80 holding position.

24. In a hydraulic elevator, a hydraulically actuated car, a constant speed reversible electric motor, a controlling valve operatively connected to the motor to be shifted thereby and shiftable from an intermediate holding position in one direction to an inlet position and in the opposite direction to an outlet position, a pivoted up direction limit switch blade, a pivoted down direction limit 90 switch blade, a pivoted reversing switch blade, a series of relay switches, one for each floor, a series of holding magnets, one for each relay, a magnetically actuated up direction switch, a magnetically actuated down 95 direction switch, a series of floor starting switches, one for each floor, a series of starting switches on the car, one for each floor, a series of stop switches, one for each floor, means whereby to energize the corresponding relay when the corresponding floor switch or corresponding car switch is closed, means whereby to energize the corresponding holding magnet by the actuation of the corresponding relay, means actuated 100 by the energizing of the holding magnet whereby to close a circuit through a source of power and both limit switch blades and one of the direction switches and the floor stop switch corresponding to the floor 110 switch or car switch which has been actuated, means controlled by the energizing of the direction switch causing current to flow through the motor in one direction, means automatically actuated upon a predetermined number of rotations of the motor automatically breaking the circuit through the limit and direction switches to stop the 115 motor but permitting the continued energizing of the said holding magnet, and means 120 automatically controlled by the arrival of the car at a predetermined floor acting through the corresponding floor stop switch to break the circuit through the holding magnet and complete a circuit through the reversing switch blade to thereby reverse the direction of current through the motor and shift the valve to a holding position, and 125

means for automatically breaking the circuit through the motor when the valve has reached its holding position.

25. In a hydraulic elevator, a hydraulically actuated car, a constant speed reversible electric motor, a controlling valve operatively connected to the motor to be shifted thereby from an intermediate position to an outlet or an inlet position, manually controlled means for causing the current to travel through said motor in either direction to thereby cause the motor to rotate in a selected direction and shift the valve from its holding position to its inlet or its outlet position, means automatically breaking the circuit through the motor when the valve has reached its selected position, and means for completing a reverse circuit through the motor when the car has reached a predetermined selected floor or level including a longitudinally shiftable bar having an off-set portion, means controlled by the movement of the car for shifting said bar longitudinally in one direction or the other, and a switch shifted from one position to another position by the engagement of said off-set with the switch.

26. In a hydraulic elevator, a hydraulically actuated car, a constant speed reversible electric motor, a controlling valve operatively connected to the motor to be shifted thereby from an intermediate position to an outlet or an inlet position, manually controlled means for causing the current to travel through said motor in either direction to thereby cause the motor to rotate in a selected direction and shift the valve from its holding position to its inlet or its outlet position, means automatically breaking the circuit through the motor when the valve has reached its selected position, means for completing a reverse circuit through the motor when the car has reached a predetermined selected floor or level including a longitudinally shiftable bar having an off-set portion, means controlled by the movement of the car for shifting said bar longitudinally in one direction or the other, a switch shifted from one position to another position by the engagement of said off-set with the switch, and means automatically breaking said last completed circuit after the motor has rotated a sufficient number of revolutions to carry the valve to its holding position.

27. In a hydraulic elevator, a hydraulically actuated car, a constant speed reversible electric motor, a controlling valve operatively connected to the motor to be shifted thereby from an intermediate position to an outlet or an inlet position, manually controlled means for causing the current to travel through said motor in either direction to thereby cause the motor to rotate in a selected direction and shift the valve from

its holding position to its inlet or its outlet position, means automatically breaking the circuit through the motor when the valve has reached its selected position, means for completing a reverse circuit through the motor when the car has reached a predetermined selected floor or level including a longitudinally shiftable bar having an off-set, a screw-threaded traveler connected to the bar, a worm engaging the traveler, means operatively connected to the car for causing the rotation of the worm in one direction or the other as the car ascends or descends, and a switch adapted to be shifted by the movement of the off-set portion of said bar with the switch when the car has reached a predetermined floor.

28. In a hydraulic elevator, a hydraulically actuated car, a reversible constant speed electric motor, a controlling valve operatively connected to the motor to be shifted thereby from an intermediate holding position in one direction to an inlet position and in the opposite direction to an outlet position, a series of manually operable floor switches, one located on each floor, a series of manually operable switches corresponding to the several floors and located in the car, means actuated by the closing of any floor switch or any one of the car switches to close a circuit in a predetermined direction through the motor to thereby cause the valve to shift toward its inlet position or its outlet position, means automatically breaking the circuit through the motor when the valve has reached its selected position, means for completing a reverse circuit through the motor when the car has reached a floor corresponding to the car switch which has been closed or the floor switch which has been closed including a series of floor stop switches corresponding in number to the number of floors, an actuating member having an off-set portion adapted to successively engage said floor switches as the member is shifted in one direction or the other, car actuated means for shifting said member, and means for automatically breaking said last named circuit through the motor when the valve has reached its holding position.

29. In a hydraulic elevator, a hydraulically actuated means, a constant speed electric motor, a controlling valve operatively connected to the motor to be shifted thereby and shiftable from an intermediate holding position to an inlet position or an outlet position, a series of motor starting switches located on each floor, a series of motor starting switches located within the car and corresponding in number to the floors, means actuated by the closing of one of the floor switches and closing a circuit through the motor to cause it to operate in a predetermined direction to thereby shift the valve

from its holding position to its inlet or its outlet position, means operated automatically to break said circuit through the motor when the valve has shifted from its 5 predetermined to its selected position to thus permit the car to ascend or descend, means breaking the circuit through all of the starting floor buttons and through any one of the floor switches when the circuit 10 has been completed through the motor to cause the shifting of the valve from its intermediate holding position, means completing a reverse circuit through the motor

when the car has reached a floor corresponding to that of the actuated switch to thereby cause the valve to return to its holding position, means then acting to automatically break the circuit through the motor when the valve has reached its holding position, and means again rendering the floor 20 switches active when the valve has reached its holding position.

In testimony whereof I hereunto affix my signature.

GEORGE LAWRENCE SLACK.
